[57] CLAIM

The ornamental design for an arthroscopic surgical retractor, as shown and described.

DESCRIPTION

FIG. 1 is a perspective view of an arthroscopic surgical retractor; showing my new design;

FIG. 2 is a side elevational view thereof;

FIG. 3 is a top plan view thereof;

FIG. 4 is a bottom plan view thereof;

FIG. 5 is a right end view of an arthroscopic surgical retractor; and

FIG. 6 is a left end view thereof.
